UNITED STATES PATENT OFFICE.

WILLIAM F. SCHMALZ, OF ROCKVILLE, AND ROBERT E. DODD, OF HARTFORD, CONNECTICUT, ASSIGNORS, BY MESNE ASSIGNMENTS, TO COLT'S PATENT FIRE ARMS MANUFACTURING CO., OF HARTFORD, CONNECTICUT, A CORPORATION OF CONNECTICUT.

MOLD FOR MUSICAL-INSTRUMENT MOUTHPIECES.

Application filed September 11, 1926. Serial No. 134,855

The invention is particularly applicable to a mold for molding a mouth piece for a musical instrument such as a clarinet or saxophone, but it is to be understood that the invention is not necessarily limited to mouth pieces for the instruments mentioned. It is further to be understood that the invention in its broader aspects may be applicable to the molding of other articles similar in shape to musical instrument mouth pieces.

The principal object of the invention is to provide a mold for musical instrument mouth pieces or similar articles so that these articles can be satisfactorily made from molded material without excessive cost and without the necessity for any considerable amount of machine work or other finishing work after the molding operation.

Further and more specific objects of the invention will be apparent from the following specification and claims.

In the accompanying drawings we have shown one form of mold adapted for molding the mouth piece of a clarinet, but it will be understood that the drawings are intended for illustrative purposes only and that, without departing from the spirit of the invention as set forth in the claims, the shape of the mouth piece can be varied and the details of construction of the mold itself can be varied.

Of the drawings:

Fig. 1 is a perspective view of a mouth piece such as can be molded in accordance with the invention.

Fig. 2 is a vertical transverse sectional view through a mold embodying the invention, the view being taken along the line 2—2 of Fig. 3.

Fig. 3 is a combined elevational and longitudinal sectional view of the mold, the section being taken along the line 3—3 of Fig. 2.

Fig. 4 is a horizontal sectional view taken along the line 4—4 of Fig. 2.

Fig. 5 is a view showing the same parts as Fig. 2, but showing them separated from each other.

Figs. 6, 7 and 8 are transverse sectional views showing successive steps in the assembly and use of the mold during the molding operation.

Fig. 9 is a transverse sectional view showing one of the steps in the disassembly of the mold preparatory to the removal of the molded article.

Referring to Fig. 1 of the drawings, M represents a mouth piece for a clarinet, this mouth piece being of conventional design. It is provided at its end with a tubular body *a* which is provided at its end with a diagonal wall *b* and which at the side opposite the wall *b* is formed with a flat surface or "lay" *c*. Formed on the mouth piece adjacent the flat surface or "lay" *c* is an opening *d* which extends diagonally inward and upward and communicates with the main central opening through the body portion *a*. Adjacent the upper and inner body portion *a* is a coupling flange *e* which is of smaller diameter than the body portion *a* and which is ordinarily provided with a series of annular grooves at *f*.

Referring to Figs. 2 to 5 of the drawings, the mold includes a body member 1, having a vertical recess 2 therein conforming to the exterior contour of the major portion of the mouth piece or other article to be molded. As a matter of convenience of construction the recess 2 is initially extended entirely through the body member from the top to the bottom thereof and thereafter the lower portion of the recess is closed by means of a plug 3. The upper portion of the plug is formed at an angle so as to conform to the exterior surface of the wall *b* of the mouth piece.

The body member also has formed therein a vertical slot 4 which communicates with the recess 2. A vertical plate 5 is provided which is adapted to fit and close the said slot 4, this plate being laterally movable relatively to the body portion during the removal and disassembly of the mold. Preferably the inner surface 6 of the plate is so positioned and shaped as to form the flat surface or "lay" *c* of the mouth piece to be molded.

Carried by the plate 5 is a core lug 7 which, when the plate is in assembled position, projects laterally into the recess 2. This core lug is adapted to form the lateral opening *d* in the mouth piece and for a mouth piece of the type illustrated the core lug projects not only laterally but also upward from its point of connection with the plate. Thus the lug is adapted to form an inner and upward inclined lateral opening in the mouth piece.

When the lug 7 projects not only inward but also upward as shown and described, we prefer to so construct the slot 4 and the plate 5 that they taper from the bottom toward the

top. This not only facilitates the assembly and disassembly of the parts as will presently appear, but it also assists in giving the correct width for the flat surface *c* of the mouth piece.

The mold also includes a depending core rod 8 which is movable vertically into and out of engagement with the core lug 7. This core rod 8 is adapted to form the central opening 10 in the body portion *c* of the mouth piece which opening communicates with the lateral opening *d* formed by the core lug 7. Preferably and as clearly shown in Fig. 3, the core rod 8 is of greater diameter than the width of the lug 7 and it has a transverse slot 9 at its lower end adapted to receive therein the upper portion of the lug 7. The depending portions of the rod 8 at the sides of the slot are preferably rounded. These portions form spherical surfaces at the lower end of the central opening in the mouth piece, which spherical surfaces lie at opposite sides of the opening *d*.

There is also provided an upper body member 10 which is provided with means conforming to the contour of the projecting flange portion *e* of the mouth piece. Suitable means, such as dowel pins 11, 11 are provided for properly locating the upper body member 10 with respect to the lower body member 1, and clamping means such as tapered clamps 12 are provided for holding the two body members together. For forming the grooves *f* in the mouth piece the body member 10 is provided with a segmental ring 13. This ring is removable from the body member 10 and the parts of the ring are separable from each other in order that they may be removed from the finished article.

The body member 10 is provided with a vertical recess 14 concentric with the seat for the ring 13 and the before-mentioned core rod 8 extends vertically through this recess 14. Preferably there is a bushing 15 separate from the rod 8 but surrounding and fitting it so as to permit relative sliding movement. The exterior surface of the bushing 15 slidably fits the opening 14 in the body member 10.

In addition to the parts already described there is preferably provided a base plate 16 to which the vertical plate 5 is secured, a plate 17 to which the bushing 15 is secured, and a plate 18 to which the rod 8 is secured. The plates 16, 17 and 18 are preferably provided with the usual holes (not shown) which are adapted to permit the use of jigs of the usual type for separating the parts of the mold.

In order that the plate 5 may be held in the proper assembled relation with the body member 1, the said plate is provided with at least one and preferably two transverse holes perpendicular thereto and the body member 1 is provided with similar holes registering therewith. The said holes are tapered so as to be adapted to receive taper dowel pins 20,

20 which can be driven into place when the mold is being assembled and which can be driven out when the mold is to be disassembled. Preferably in addition to the dowel pins we also provide transverse holes for receiving a tie bolt 21 which serves to prevent the body member from spreading or warping in such a way as to increase the width of the slot 4.

We have thus far described the mold as being adapted for the molding of a single mouth piece. We prefer, however, to provide a multiple mold and we have accordingly shown such a multiple mold in Figs. 3 and 4. It will be understood that when a multiple mold is provided there is for each additional article a duplication of the recesses in the body members and a duplication of all of the parts directly associated with such recesses. It will be understood, however, that all of the plates 5 are carried by a single base plate 16, that all of the bushings 15 are carried by a single plate 17 and that all of the rods 8 are carried by a single top plate 18. It will further be understood that a single pair of taper dowel pins 20, 20 and a single tie bolt 21 suffice for holding all of the plates 5 in proper relation to the body member 1.

In using the mold the plate 5 is entered in the slot 4 and the dowel pins 20, 20 and the tie bolt 21 are put in place to hold the plate and the body member in the proper assembled relation. When thus assembled the body member 1 rests upon the base 16 as shown in Fig. 6. The next step is to place the upper body member 10 in place on the lower body member 1 with the segmental ring 12 in place as clearly shown in Fig. 7. The body members 10 and 1 are clamped together as already described.

When the parts have been assembled as shown in Fig. 7 the moldable material is introduced either in powder or briquette form, preferably the former. Then the bushing 15 is entered in the recess 14 of the upper body member 10 as shown in Fig. 8 and the rod 8 is entered in the bushing 15 as shown in the same figure. The two plates 17 and 18 will be initially separated from the body member 10 and preferably separated from each other even when the plate 18 has been lowered so that the rod 8 initially engages the moldable material. The entire mold is then placed in a press and heated and closed in the usual manner, the parts moving to the relative positions shown in Figs. 2 and 3. The bushing 15 and the rod 8 cooperate to compress the moldable material, and the rod 8 is forced downward through the material into engagement with the lug 7. The rod 8 thus forms the central opening through the article.

When the molding operation is complete, the parts of the mold are separated so as to remove the lug 7 and the rod 8 from the mold in different directions. The sequence of steps

in disassembling the mold may be varied but one such sequence will be described. The rod 8 and the bushing 15 may be withdrawn first, either together or in sequence as may be most convenient. The lug 7 may be withdrawn next, this being effected by separating the plate 5 and the body member 1 from each other in a diagonal direction as shown in Fig. 9. This relative diagonal movement is brought about in part by reason of the engagement of the lower inclined surface of the lug 7 with the corresponding inclined surface of the mouth piece adjacent the opening *d*. Finally the clamps 12 may be removed to permit the separation of the body members 10 and 1 and the removal of the ring 13.

It will be understood that the term "vertical" and "horizontal" and other similar terms as used herein are intended merely to indicate the relationship of the several parts and are not to be construed as otherwise limiting the invention.

What we claim is:

1. A mold for the mouth piece of a musical instrument or for a similar article, comprising in combination a body member having a vertical recess therein conforming to the exterior contour of the major portion of the article to be molded and having at one side a vertical slot therein communicating with the recess at one side thereof, a vertical plate adapted to fit and close the said slot and relatively movable laterally with respect to the body member during assembly and disassembly, the inner edge of the plate when in assembled relation with the body member forming an exterior flat surface on the said article, a core lug carried by the plate and projecting laterally into the recess when the body member and plate are in assembled relation so as to form a lateral opening in the said article, and a depending central core rod movable vertically into or out of engagement with the said core lug, the said rod forming a central opening in the said article communicating with the lateral opening formed by the lug.

2. A mold for the mouth piece of a musical instrument or for a similar article, comprising in combination a body member having a vertical recess therein conforming to the exterior contour of the major portion of the article to be molded and having at one side a vertical slot therein communicating with the recess at one side thereof, a vertical plate normally fitting and closing the said slot and carrying a core lug normally projecting into the recess in a diagonal inward and upward direction so as to form an inward and upward inclined lateral opening in the said article, the said body member and the said plate being adapted to be separated by relative movement in a diagonal direction approximating the direction of projection of the lug, and a depending core rod movable

vertically into or out of engagement with the said core lug and adapted to form a central opening in the said article communicating at its bottom with the upper and inner end of the lateral opening formed by the lug. 70

3. A mold for the mouth piece of a musical instrument or for a similar article, comprising in combination a body member having a vertical recess therein conforming to the exterior contour of the major portion of the article and having at one side a vertical slot therein communicating with the recess at one side thereof, a vertical plate adapted to fit and close the said slot and relatively movable laterally with respect to the body member during assembly and disassembly, a core lug carried by the plate and projecting laterally into the recess when the body member and plate are in assembled relation so as to form a lateral opening in the said article, and a depending central core rod movable vertically into or out of engagement with the said core lug, the said rod being of greater diameter than the width of the lug and being slotted at its lower end to receive the upper portion of the lug so that the rod forms a relatively large central opening in the said article extending downward below the upper portion of the lateral opening formed by the lug and communicating therewith. 95

4. A mold for the mouth piece of a musical instrument or for a similar article, comprising in combination a lower body member having a vertical recess therein conforming to the exterior contour of the lower portion of the article to be molded and having at one side a vertical slot therein communicating with the recess at one side thereof, a vertical plate adapted to fit and close the said slot and relatively movable laterally with respect to the body member during assembly and disassembly, a core lug carried by the plate and projecting laterally into the recess when the body member and plate are in assembled relation so as to form a lateral opening in the said article, an upper body member separate from the lower body member and having a vertical opening therein conforming to the exterior contour of the upper portion of the said article, and a depending central core rod movable vertically into or out of engagement with the said core lug, the said rod being guided in its movement by the said upper body member and when in its lower position forming a 110 central opening in the said article communicating with the lateral opening formed by the lug.

5. A mold for the mouth piece of a musical instrument or for a similar article, comprising in combination a lower body member having a vertical recess therein conforming to the exterior contour of the lower portion of the article to be molded and having at one side a vertical slot therein communicating 125

with the recess at one side thereof, a vertical plate adapted to fit and close the said slot and relatively movable laterally with respect to the body member during assembly and 5 disassembly, a core lug carried by the plate and projecting laterally into the recess when the body member and plate are in assembled relation so as to form a lateral opening in the said article, an upper body member separate 10 from the lower body member and having a vertical opening therein conforming to the exterior contour of the upper portion of the said article, a bushing vertically movable in the opening in the upper body member and adapted to be moved downward to compress moldable material in the mold and 15 to form the upper end face of the said article, and a depending central core rod movable vertically into or out of engagement with the said core lug, the said rod fitting 20 the opening in the bushing and being vertically movable therein and when in its lower position forming a central opening in the said article communicating with the lateral 25 opening formed by the lug.

6. A mold for the mouth piece of a musical instrument or for a similar article, comprising in combination a lower body member having a vertical recess therein conforming 30 to the exterior contour of the lower portion of the article to be molded and having at one side a vertical slot therein communicating with the recess at one side thereof, a vertical plate adapted to fit and close the said slot and relatively movable laterally with respect to the body member during assembly and 35 disassembly, a core lug carried by the plate and projecting laterally into the recess when the body member and plate are in assembled relation so as to form a lateral opening in the said article, an upper body member separate 40 from the lower body member and having a vertical opening therein conforming to the exterior contour of the upper portion of the said article, the said body member including a removable segmental ring adapted to form annular grooves in the said article, a bushing vertically movable in the opening in the upper body member and adapted to be moved downward to compress moldable material in the mold and 45 to form the upper end face of the said article, the lower end face of the bushing when in final position engaging the upper face of the ring, and a depending central core rod movable vertically into or out of engagement with the said core lug, the said rod fitting the opening in the bushing and being vertically movable therein and when in 50 its lower position forming a central opening in the said article communicating with the lateral opening formed by the lug.

7. A mold for the mouth piece of a musical instrument or for a similar article, comprising 55 in combination a body member having a

vertical recess therein conforming to the exterior contour of the major portion of the article to be molded and having at one side a vertical slot therein communicating with the recess at one side thereof, a vertical plate adapted to fit and close the said slot and relatively movable with respect to the body member during assembly and disassembly, the said slot and the said plate being similarly tapered to facilitate the said relative movement, a core lug carried by the plate and projecting laterally into the recess when the body member and plate are in assembled relation so as to form a lateral opening in the said article, and a depending central core rod 70 movable vertically into or out of engagement with the said core lug, the said rod forming a central opening in the said article communicating with the lateral opening formed by the lug. 75

8. A mold for the mouth piece of a musical instrument or for a similar article, comprising in combination a body member having a vertical recess therein conforming to the exterior contour of the major portion of the article to be molded and having at one side a vertical slot therein communicating with the recess at one side thereof, a vertical plate normally fitting and closing the said slot and carrying a core lug normally projecting 80 into the recess in a diagonal inward and upward direction so as to form an inward and upward inclined lateral opening in the said article, the said body member and the said plate being adapted to be separated by relative movement in a diagonal direction approximating the direction of projection of the lug and the said slot and the said plate being tapered from the bottom thereof toward the top to facilitate the said relative movement, and a depending core rod movable vertically into or out of engagement with the said core lug and adapted to form a central opening in the said article communicating at 85 its bottom with the upper and inner end of the lateral opening formed by the lug. 90

9. A mold for the mouth piece of a musical instrument or for a similar article, comprising in combination a body member having a vertical recess therein conforming to the exterior contour of the major portion of the article to be molded and having at one side a vertical slot therein communicating with the recess at one side thereof, a vertical plate adapted to fit and close the said slot and relatively movable with respect to the body member during assembly and disassembly, the said body member and plate respectively having holes therein which are perpendicular to the plate and which register when the body and plate are in assembled relation, a removable dowel pin adapted to extend through the said registering holes to hold the body member and plate in the said relative position, a core lug carried by the plate 100

and projecting laterally into the recess when the body member and plate are in assembled relation so as to form a lateral opening in the said article, and a depending central core rod movable vertically into or out of engagement with the said core lug, the said rod forming a central opening in the said article communicating with the lateral opening formed by the lug.

10 10. A mold for the mouth piece of a musical instrument or for a similar article, comprising in combination a body member having a vertical recess therein conforming to the exterior contour of the major portion of the article to be molded and having at one side a vertical slot therein communicating with the recess at one side thereof, a flat base

adapted for supporting the said body member, a vertical plate secured to the base and adapted to fit and close the said slot in the body member, the said base and plate being movable relatively to the body member during assembly and disassembly, a core lug carried by the plate and projecting laterally into the recess when the body member and plate are in assembled relation so as to form a lateral opening in the said article, and a depending central core rod movable vertically into or out of engagement with the said core lug, the said rod forming a central opening in the said article communicating with the lateral opening formed by the lug.
